UNITED STATES PATENT OFFICE

1,972,352

MINING MACHINE TRUCK

Ernst F. Muller, Columbus, Ohio, assignor to The Jeffrey Manufacturing Company, a corporation of Ohio

Application March 19, 1932, Serial No. 599,964

25 Claims. (Cl. 105—161)

My invention relates to improvements in truck mechanism which are adapted to transport a mining machine from place to place in a mine, particularly a mining machine of the type adapted to be operated by sliding the same by means of rope gearing on its own bottom over the mine bottom during cutting operations.

One of the objects of the invention is the provision of improved and efficient means for loading and unloading the mining machine onto a transporting truck and from the same.

A further object of the invention is the provision of loading and unloading mechanism on a mining machine truck to enable the loading and unloading of a mining machine with a minimum head room.

More particularly it is the object of the present invention to provide mechanism on a mining machine truck for loading and unloading a mining machine by moving the same horizontally off the truck during unloading and onto the truck during loading so that tilting will occur on such an axis as to require minimum head room and therefore enabling the loading and unloading to take place in a low roof mine.

Other objects of the invention will occur hereinafter, the novel features and combinations being set forth in the appended claims.

In the accompanying drawings Fig. 1 is a plan view of a loading and unloading mining machine truck embodying the features of my invention;

Fig. 2 is an elevational view of the mining machine truck with a mining machine thereon and the parts in position for transportation in a mine;

Fig. 3 is an elevational view showing the position of the mining machine on the improved mining machine truck at the time that the forward end of the mining machine is tilted downwardly;

Fig. 4 is an enlarged elevational view of the forward end of the unloading mechanism shown in Fig. 3;

Fig. 5 is an enlarged sectional elevation on the line 5—5 of Fig. 4 looking in the direction of the arrows;

Fig. 6 is a detached view of the forward end of the unloading mechanism showing the position of the parts before a mining machine is moved onto the loader or off the same; and

Fig. 7 is an enlarged detached sectional view of the structure as shown in Fig. 2 while in traveling position or in position for transportation in the mine.

Referring to Fig. 3, 8 designates the truck

which is provided with wheels 9, 9 for traveling on the mine track 10. The front and rear axles 11 and 12 of the truck may be geared together by means of the sprocket chain 13 as shown in Fig. 1. A brake 14 may be associated with one 60 of the wheels 9 as shown in Fig. 1. The brake 14 may be operated by means of the lever 16 shown in Figs. 1 and 2 as being connected through the transverse shaft 17 to the adjustable link 18. The brake may be held applied as illustrated at 65 19 in Fig. 1.

During transportation of the truck, gearing 20 connected to the axle 12 may be relied on to operate the cable reel 21 when the clutch 22 is thrown in.

When the mining machine 23 of the type above referred to is mounted on the truck as shown in Fig. 2 a take off sprocket 24 may be connected by means of a sprocket chain diagrammatically illustrated at 25 to a sprocket wheel 26 on the rear 70 axle 12 of the truck. By controlling the electric motor on the mining machine 23 the sprocket 24 may be rotated to transmit power to the axles 11 and 12 of the truck. The truck propelling mechanism may therefore be operated by the motor of the mining machine 23 and during transportation of the truck with the mining machine thereon the electric cable for the motor may be paid out or wound up by rotation of the cable reel 21.

Pivoted at 26' to the forward end of the truck 8 is sectional guiding mechanism 27 comprising a horizontal skid 28 and an auxiliary skid 29.

The truck 8 is provided with lateral longitudinal guides 30, 30 as shown in Fig. 1. The horizontal skid 28 is likewise provided with guides 31, 31 which are in alinement with the guides 30, 30 when the skid 28 is in horizontal position.

When the sprocket chain 25 is removed from the sprocket 24 one of the ropes of the mining 95 machine 23 may be unreeled from the rope drum 32 and its free end connected to an anchorage in the mine extraneous to the truck and in advance of the mine track 10. Now upon operating the motor of the mining machine 23 to rotate the 100 rope drum 32 the mining machine may be pulled off the truck 8 while the brake 14 is applied to the brake pulley 9 to hold the truck stationary or anchored on the mine track.

It should be particularly noted that the sectional skid 27 is pivoted at 26' intermediate the ends of the horizontal skid 28. The guides 30, 30 remain in alinement with the guides 31, 31 until the mining machine 23 is in the position shown in Fig. 3 when the center of gravity of the mining 110

machine and the skid on which it is then mounted, is in advance of the pivot 26'.

It is desired to guide the mining machine along the horizontal skid 28 in a horizontal path so that when the mining machine is tilted to the position shown in Fig. 3 the rear upper end of the mining machine will move along a relatively small arc. In other words, by advancing the mining machine 23 along a horizontal path so that its rear end will be closer to the pivot 26' before tilting occurs, the height to which the rear end of the mining machine reaches will be lessened. I therefore provide an auxiliary skid 29 and mechanism associated therewith for holding the skid 28 horizontal to delay the tilting of the mining machine in the unloading operation until the rear end of the mining machine is closer to the pivot 26'.

The auxiliary skid 29 is pivoted at 30' to the horizontal skid 28, as shown in Figs. 2 and 3. Extending forwardly from the horizontal skid 28 are two spaced-apart bearings 28', 28" as shown in Fig. 5. A shaft 31' is provided with enlarged extensions 32', 32" concentric therewith and journaled in the bearings 28', 28".

To the outer ends of the enlargements 32', 32" are eccentrically connected the operating shafts 33, 33 to which are keyed the sleeves 34, 34. To one of these sleeves 34 is secured an operating arm or lever 35. The sleeves 34, 34 are journaled in the bearings 36, 36 which are integral with or rigidly secured to the upright arms 29', 29" of the auxiliary skid 29.

At opposite sides of the forward end of the horizontal skid 28 are mounted springs one of which is shown in elevation at 37 in Fig. 6. The rear end of this spring engages the standard 38 fixed to the horizontal skid 28. The spring surrounds a rod 39 the rear end of which extends through an opening in the standard 38 and is screw threaded to receive the adjusting nut 40 and the lock nut 41. The forward end of the rod 39 is secured to the head 42 which is pivoted to the cross pin 43 as shown in Figs. 5 and 6. Since the pins 43, 43 are mounted in the upright arms 29', 29" the springs 37, being compression springs, urge the auxiliary skid 29 into angular relation with the horizontal skid 28 when the auxiliary skid is released and free to move on its pivot 30'.

It should be particularly noted that the auxiliary skid 29 is mounted to swing either on the pivot 30' or on the pivot 43. When the lever 35 is in the position shown in Fig. 6 the eccentric pin 33 has such relation to the enlargements 32' as to enable the springs 37 to swing the auxiliary skid 29 into the angular position shown in Fig. 6. By moving the lever 35 180° from the position shown in Fig. 6, the eccentric pin 33 will remain in fixed relation to the horizontal skid 28. The enlargements 32' will then act as eccentrics to swing the auxiliary skid 29 on the pivot 43 to the traveling position shown in Figs. 2 and 7. This movement of the auxiliary skid 29 from its position in Fig. 6 to its position in Figs. 2 and 7 may be made without compressing the springs 37, and may therefore be accomplished with little effort.

In the unloading operation the truck with the mining machine thereon travels along the mine track 10 with the auxiliary skid in traveling position as shown in Figs. 2 and 7 but before the haulage rope extending from the winding drum 32 is pulled to remove the mining machine from the truck the lever 35 is swung from its position shown in Fig. 2 to its position shown in Fig. 6. The toe 44 of the auxiliary skid will then engage the floor

45 of the mine chamber in advance of the mine track. Now upon applying the brakes 14 to hold the truck stationary the mining machine may be pulled along the guides 30 and 31 and by reason of the springs 37 acting between the auxiliary skid 29 and the horizontal skid 28 the latter will be held horizontal until the counterbalancing action of the springs 37 is overcome by the center of gravity of the mining machine advancing sufficiently beyond the pivot 26'. It will thus be seen that the sectional unloading guideway having the yielding flexible joint enables the mining machine to be unloaded in a very low roof chamber. For instance, in Fig. 3 the roof of the mine chamber may be as low as that indicated at 46 because before the mining machine tilts on the pivot 26' to its position shown in Fig. 3 the rear upper end of the mining machine will be well advanced to shorten the arc of such upper rear end of the mining machine on the pivot 26'.

Similar advantages are obtained in loading the mining machine onto the transporting truck. The haulage rope extending from the rope drum 32 may be connected to either hook 47 on the auxiliary skid 29. During this time the lever 35 occupies the position shown in Fig. 6 so that the skid 28 will be held in horizontal position with its guides 31 in alignment with the guides 30 and the toe 44 in contact with the floor 45. When the mining machine has been pulled to a position near the sectional skid the haulage rope may be extended between the guides 30, 31 on one side and the guides 30, 31 on the other side of the truck to the anchorage shown at 48 in Fig. 1. Now upon continuing the pull on the haulage rope the mining machine is moved onto the skid 28 to its position shown in Fig. 3. During the hauling of the mining machine onto the skid 28 the springs 37 are compressed and the sectional skid collapsed into the position shown in Fig. 3. The springs 37 being under compression act to urge the toe 44 against the floor 45.

When the center of gravity of the mining machine reaches a certain relation to the pivot 26' the springs 37 effect a tilting of the skid 28 to horizontal position on the pivot 26' before the upper rear end of the mining machine extends to any higher position than that shown in Fig. 3. In the loading operation, therefore, the springs 37 act to advance the time when the center of gravity of the mining machine acts to tilt the mining machine to a horizontal position. After the mining machine is tilted to its horizontal position it may be drawn back to its transporting position shown in Fig. 2 and then by shifting the lever 35 to the position shown in Fig. 2 the auxiliary skid 29 will be in traveling position.

The springs 37 will be under compression at all times and the amount of compression regulated by reason of the nuts 40, 41, but it should be understood that when the skid 29 is moved from its position shown in Fig. 6 to its traveling position shown in Fig. 7 the compression of the springs 37 is not increased because the swinging upwardly of the toe 44 by means of the lever 35 is on the pivot 43 which remains at the same distance from the standard 38 in Fig. 7 as the distance shown in Fig. 6. The continuity of the lateral edges of the main and auxiliary guides remains interrupted at 49 in the traveling position shown in Fig. 7. The interrupting spaces are wider as shown at 50 in Fig. 6 but when the sectional flexible loading and unloading guiding mechanism is collapsed or straightened out by the weight of the mining ma-

- chine thereon as shown in Fig. 3, the gaps or spaces between the lateral edges of the guides are closed.
- It should also be noted that when the mining machine unloaded, the springs 37 will act to cushion the tilting of the machine from its horizontal position and cause such tilting to take place gradually instead of suddenly when the center of gravity passes over the pivot 26'. In the loading operation the movement from inclined position of the mining machine to horizontal position will also be gradual.
- In some instances the ground or floor 45 in advance of the mine track may not be sufficiently hard to prevent the toe 44 from sinking down during the loading or unloading operations. When the floor in advance of the mine track is relatively soft an iron or steel rod or pipe may be inserted through the holes 51 in the vertical plates 52 which depend from opposite edges of the auxiliary skid 29 and such rod or pipe be permitted to project beyond the sides of such auxiliary skid. The vertical plates 52 may be connected by the reinforcing pipe 53 as shown in Fig. 7.
- With this arrangement the truck should be so positioned on the mine track 10 that the cross rod or pipe in the holes 51 will be above the rails. Then when the skid 28 is tilted down a very firm foundation for the auxiliary skid will be afforded by the rod or pipe engaging the forward end portions of the rails of the mine track during loading and unloading operations of the mining machine.
- Obviously those skilled in the art may make various changes in the details and arrangement of parts without departing from the spirit and scope of the invention as defined by the claims hereto appended and I wish therefore not to be restricted to the precise construction herein disclosed.
- Having thus described and shown an embodiment of my invention, what I desire to secure by Letters Patent of the United States is:
1. In mining apparatus, the combination with a truck, of a skid connected thereto, and means connected to said skid for yieldingly holding the outer end thereof elevated until the center of gravity of a mining machine moved from the truck onto said skid tilts the skid down by causing said means to yield.
  2. In an unloading skid, the combination with a guideway adapted to be connected to the support from which a load is to be removed, of an auxiliary guideway pivoted thereto, yielding means for holding the guideways in angular relation until the weight of the load overcomes such means, and mechanism on said auxiliary guideway for carrying a cross-support in position to engage the rails of a mine track.
  3. In unloading apparatus, the combination with a pivoted guide support, of an auxiliary ground engaging guide support, and a yielding knuckle joint between said guide supports for holding the pivoted guide support horizontal while the other support engages the ground.
  4. In unloading mechanism, the combination of a pivoted skid having a knuckle joint intermediate its ends, and a spring for holding the joint angular until the load on the skid overcomes the action of said spring and straightens out the skid.
  5. An unloading skid comprising pivoted sections, and a spring for holding said sections in angular relation with one section horizontal and the other in contact with the ground until the load overcomes the action of the spring and straightens out the skid.
  6. In mining apparatus, the combination with a truck, of a skid pivotally connected thereto and comprising pivotally connected sections, and a spring normally holding said sections in angular relation.
  7. In mining apparatus, the combination of an unloading skid comprising pivoted sections, one section being horizontal and the other inclined, and means for holding said sections in angular relation until a predetermined weight thereon straightens out the skid by inclining the horizontal section.
  8. In mining apparatus, the combination of a loading and unloading skid comprising pivoted sections, one horizontal and the other inclined, and means normally flexing said skid but yielding to a predetermined weight on the skid to straighten out the same by inclining the horizontal section and bringing both sections into alignment with each other.
  9. In mining apparatus, the combination of a loading and unloading skid comprising pivoted sections, of yielding means for holding the sections in angular relation, and manually operable means for positively moving the sections into horizontal alignment without interference from said yielding holding means.
  10. In mining apparatus, the combination with a truck, of unloading guiding mechanism pivotally connected thereto, said guiding mechanism comprising sections pivoted to each other, and a spring for holding the sections in angular relation until the weight of the mining machine acts against said spring to tilt the guiding mechanism on its pivot and aligning said sections.
  11. In mining apparatus, the combination with a truck, of sectional guiding mechanism pivotally connected thereto, and means between the sections to hold them in angular relation with the pivoted section horizontal and the other section in engagement with the ground until the load moving off the truck a predetermined distance tilts the horizontal section and alines the two sections.
  12. In mining apparatus, the combination with a truck, of guiding mechanism pivoted to said truck and comprising sections pivoted to each other, and a spring between the sections to hold the same in angular relation until the load is moved off the truck a predetermined distance.
  13. In mining apparatus, the combination with a truck adapted to support and transport a mining machine, of guiding mechanism pivoted to said truck, and means for holding the receiving portion of said guiding mechanism in substantially horizontal position until the overbalancing of the mining machine on the guiding mechanism tilts such receiving portion downwardly thereby lowering the necessary headroom for unloading the mining machine.
  14. In mining apparatus, the combination with a truck adapted to support and transport a mining machine, of guiding mechanism comprising a horizontal skid pivoted to said truck and a floor engaging extension pivoted to said skid, and a spring to yieldingly hold said skid in horizontal position until the overbalancing weight of the mining machine overcomes the action of said spring whereby tilting of the mining machine with said skid is delayed until the rear end of the mining machine is nearer the pivot between said skid and said truck.
  15. In mining apparatus, the combination with a truck adapted to support a mining machine for transportation, of guiding mechanism comprising

- a receiving section pivoted to said truck and a floor engaging section pivoted to said receiving section, a spring between said sections for holding them in angular relation, and manually operated mechanism for straightening out the floor section to hold the same up for transportation of the truck. 80
16. In mining apparatus, the combination with a truck adapted to support a mining machine for transportation, of guiding mechanism comprising pivotally connected sections, a spring for normally holding said sections in angular relation, and an abutment for positively limiting the straightening out of said sections relative to each other. 85
17. In mining apparatus, the combination with a truck adapted to support a mining machine for transportation, of guiding mechanism comprising two sections pivotally connected at a predetermined axis, a spring between said sections, and means comprising eccentric mechanism for straightening out the sections independently of said spring and another axis spaced from said first-named axis. 90
18. In apparatus for unloading from trucks, the combination with guiding mechanism comprising two sections, of a pivotal connection between said sections, a spring between said sections, a pivotal connection between said spring and one of said sections, and eccentric mechanism associated with said first-named pivotal connection for moving said sections into alinement on the said first-named pivotal connection independently of said spring. 95
19. In mining apparatus, the combination with a truck adapted to support and transport a mining machine, of guiding mechanism pivoted to said truck and comprising two sections, a pivotal connection between said sections, a spring between said sections to move the outer section on said pivotal section into ground engaging position while holding the other section horizontal, a pivotal connection between the outer end of said springs and said outer section, and eccentric mechanism for moving said outer section on said last-named pivotal connection to horizontal position for transportation. 100
20. In mining apparatus, the combination with a truck adapted to support and transport a mining machine, of guiding mechanism comprising two sections, one section being pivoted intermediate its ends to one end of said truck and held horizontal by the weight of one end of said mining machine when on the truck, the other section being pivoted to the outer end of said first-named section, and means for yieldingly holding the said sections in angular relation with the outer section in ground engaging position. 105
21. In unloading apparatus, the combination with a portable support, of guiding mechanism mounted thereon and comprising two sections pivotally connected to each other, one section being pivotally connected intermediate its ends to one end of said portable support, means between said sections for holding the outer section in ground engaging position and the pivoted section in horizontal position, and manually operable means for holding said sections in alinement with each other. 110
22. In mining apparatus, the combination with a truck, of a skid adapted to be connected thereto in position to receive a mining machine from the said truck, and automatically operable yielding means holding the skid elevated while the mining machine is moving from its position on the truck to a position on the skid where the center of gravity of the mining machine is beyond the connection between the skid and the truck. 115
23. In apparatus for loading a mining machine onto a truck, or unloading the same therefrom, the combination with a truck adapted to travel on a mine track, of a skid for receiving a mining machine from the truck, and self-restoring yielding means for holding the outer portion of the skid elevated during the first part of the movement of the mining machine off the truck. 120
24. In mining apparatus, the combination with a truck, of a skid pivotally connected thereto and comprising pivotally connected sections, and yieldable means normally holding the said sections in angular relation. 125
25. In mining apparatus, the combination with a truck, of a skid pivotally connected thereto and comprising pivotally connected sections, and self-restoring yielding means normally holding the said sections in angular relation. 130
